H. A. DOUGLAS

REFLECTING LAMP,

APPLICATION FILED FEB. 19, 1917.

1,261,784.

Patented Apr. 9, 1918.

UNITED STATES PATENT OFFICE.

HARRY A. DOUGLAS, OF BRONSON, MICHIGAN, ASSIGNOR TO DOUGLAS & RUDD MFG. CO., OF BRONSON, MICHIGAN, A CORPORATION OF MICHIGAN.

REFLECTING-LAMP.

1,261,784.

Specification of Letters Patent.

Patented Apr. 9, 1918.

Application filed February 19, 1917. Serial No. 149,665.

To all whom it may concern:

Be it known that I, HARRY A. DOUGLAS, citizen of the United States, residing at Bronson, in the county of Branch and State 5 of Michigan, have invented a certain new and useful Improvement in Reflecting-Lamps, of which the following is a full, clear, concise, and exact description.

My invention relates to reflecting lamps, 10 some features of the invention being of particular utility in connection with electric lamps. The invention has for its object the provision of improved mechanism whereby the light source of the lamp may be adjusted in and out with respect to the reflector and where the invention is embraced in an electric lamp I also provide improved means for switching the lamp in and out of circuit. The mechanism that is employed 15 for adjusting the light source such as a lamp bulb and the mechanism which is employed for switching the lamp into and out of circuit preferably includes operating parts that are common thereto.

20 My invention in its various aspects will be fully explained in connection with the accompanying drawing and will be defined in the claims. In the drawing, which shows the preferred embodiment of the invention 25 as employed in electric lamps, Figure 1 is a side elevation, partially in section, of a reflecting lamp containing features of my invention; Fig. 2 is a longitudinal view, partially in section and partially in elevation, 30 of portions of the structure illustrated in Fig. 1; Fig. 3 is a view on line 3—3 of Fig. 6; Fig. 4 is a view on line 4—4 of Fig. 2; Fig. 5 is a view on line 5—5 of Fig. 2; and Fig. 6 is a view on line 6—6 of Fig. 2.

35 Like parts are indicated by similar characters of reference throughout the different figures.

The concave reflector 1 is received in the reflector carrying concave casing 2 here 40 shown as distinct and spaced apart from the reflector, but to which construction the invention is not to be limited. When these elements 1 and 2 are separate they are coupled in any suitable way, leaving a space intervening between the reflector and casing. The reflector includes a rearwardly extending tubular continuation 3 in fixed relation with the balance of the reflector, this continuation constituting a holder or mounting. 45

50 A spring tongue 4 is integrally formed with

a shell 5 that constitutes a holder for contact carriers, this spring tongue having ample clearance at its side margins to permit it freely to function. Some part of the tongue, such as the rear free end thereof, has a part 6 5 projecting therefrom which is narrower than the balance of the tongue and is slightly narrower than a slot 7 in the holder 3 whereby this portion may project into the slot to prevent the shell from turning with respect to the slot while at the same time the side margins of the tongue 4 are adapted to press against the side margins of the slot 7. The tongue thus presses upon a surface of the holder 3 and, where there is but one tongue, forces the shell toward the opposite side of the holder whereby the shell is held in engagement with the holder 3. The slot 7 is elongated so that the shell 5 may be moved back and forth in its holder 3 whereby in the structure illustrated the position of the lamp bulb 8 which is carried by the forward end of the shell in front of the reflector may be adjusted with respect to the reflector. The base 9 of the lamp bulb 8 constitutes the forward contact carrier and as the arrangement illustrated is a double pole arrangement this contact carrier 9 carries two rear contacts 10 and 11. The lamp base or contact carrier 9 is provided with bayonet pins 12 engageable within bayonet seats 13 constituting parts of bayonet slots 14. The rear contact carrying plug 15 within the casing 2 is provided with terminal blocks 16 having binding screws 17 by which circuit wires may be secured to the terminal blocks. These terminal blocks are cylindrical and the forward ends thereof are tubular, springs 18 being included in the tubular portions of the terminal blocks and operating to press contacts 19, 20 forwardly into engagement with the contacts 10 and 11, all of these contacts being within the casing. The springs 18 and the contacts 19 and 20 thus not only serve to establish circuit for the lamp but also operate to hold the lamp base 9 in bayonet pin and slot connection with the shell 8. 55

The plug 15 is rotatable within the rear end of the shell 5 in order that it may perform its switching function and when thus movably mounted it is provided with bayonet pins 21 and which are receivable in alternate bayonet seats 22, 23, shown in Figs. 2 and 3, the plug being inserted from the 60

front end of the shell with its pins passing along the bayonet slots 14 until they are in the zone that includes the bayonet seats 22, 23 whereafter the base of the lamp bulb is inserted in the shell with its pins 12 placed in the bayonet seats 13. The springs 18 thus not only serve to hold the bayonet pins 12 in the seats but also serve to hold the bayonet pins 21 in the seats to which they are adjusted.

It will be observed that the complementary switching contacts 10 and 19 are eccentric with respect to the shell as are also the complementary switching contacts 11 and 20 so that as the plug is turned these contacts are either brought into engagement or are separated according to the direction of movement of the switching plug 15. When the lamp is in open circuit the contacts 19 and 20 are pressed against the insulating portions of the lamp base that are adjacent the contacts 10 and 11, the springs 18 continuing to press the contacts 19 and 20 forwardly to maintain the bayonet pins upon the switching plug and upon the lamp base in the their respective bayonet seats. The shell and the parts within it are in front of the casing 2 and in order that the switching plug 15 may be turned or otherwise moved with respect to the lamp base to cut the lamp in and out of circuit I employ a motion transmitting connection, preferably in the form of a switching rod 24, which is connected at its inner end with the switching plug and which is operable from the exterior of the casing. The outer end of this switching rod desirably has a gripping head piece 25 assembled therewith. The head piece 25 has an insert 26 which has a square bore. The outer end of the rod 24 is correspondingly square so that the rod may be moved longitudinally with respect to the head piece but will turn therewith. The corners of the square end of the rod are threaded and have threaded engagement with the threaded bore of the sleeve 27. This sleeve is received within a cylindrical seat formed in the outer end of the head piece 25. The spring 27 engages the plug 15 at one end and the inner surface of the handle 21 at the other end and operates to hold the sleeve in engagement with the head piece and, through the intermediation of the sleeve, the spring operates to hold the head piece in engagement with the back end of the handle 21. By this arrangement both the head piece and the sleeve are confined in a single plane of rotation whereby the former may alone cut the lamp in and out of circuit and the latter may alone move the shell and the lamp bulb in and out, the sleeve being rotatable with respect to the head piece. The particular form of lamp illustrated is what is known as a "spot light" but to which form of lamp the invention is

not to be limited. When the lamp is in the form of a "spot light" the back element is provided with a handle 21 and this handle I preferably constitute a rearward continuation of the casing, the switching rod 24 passing through the handle to a point where it is operable from the exterior of the casing.

Any suitable means may be employed for establishing circuit relation between the contacts upon the plug 15 and the external source of current, there being illustrated a well known form of connector 15¹ which may be employed for this purpose.

Certain features of novelty herein disclosed are claimed in my co-pending application Serial No. 149,664, filed February 19, 1917.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:—

1. In a reflecting electric lamp, the combination with a reflector carrying casing; of an electric lamp bulb; a shell carrying the lamp bulb at its front end and having bayonet pin and slot connection with the base of the lamp bulb; eccentrically disposed switching contacts within the casing for cutting the lamp in and out of circuit; a plug within the casing and mounted to turn in the shell to have alternative positions to cut the lamp in and out of circuit and having bayonet pin and slot engagement with the shell in the alternative positions of the plug; a rod extending from said plug and operable from the exterior of the casing for turning the plug; spring means for holding said contacts in engagement to establish circuit and operating to hold the plug in circuit opening and circuit closing positions; a head piece for the rod and engaged with the casing to confine it to a single plane of rotation, said rod being movable longitudinally and with respect to the head piece and turning with the head piece in its various positions with respect thereto; a rotatable sleeve in threaded engagement with the rod; and a spring for maintaining the sleeve in engagement with the head piece.

2. In a reflecting electric lamp, the combination with a reflector carrying casing; of an electric lamp bulb; a shell carrying the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one upon the plug; a motion-transmitting rod

extending from the plug and operable from the exterior of the casing to turn said plug; a head piece for the rod and engaged with the casing to confine it to a single plane of rotation, said rod being movable longitudinally and with respect to the head piece and turning with the head piece in its various positions with respect thereto; a rotatable sleeve in threaded engagement with the rod; and a spring for maintaining the sleeve in engagement with the head piece.

3. In a reflecting electric lamp, the combination with a reflector carrying casing; of an electric lamp bulb; a shell carrying the lamp bulb at its front end and having bayonet pin and slot connection with the base of the lamp bulb; eccentrically disposed switching contacts within the casing for cutting the lamp in and out of circuit; a plug within the casing and mounted to turn in the shell to have alternative positions to cut the lamp in and out of circuit and having bayonet pin and slot engagement with the shell in the alternative positions of the plug; a rod extending from said plug and operable from the exterior of the casing for turning the plug; spring means for holding said contacts in engagement to establish circuit and operating to hold the plug in circuit opening and circuit closing positions; a head piece for the rod and engaged with the casing to confine it to a single plane of rotation, said rod being movable longitudinally and with respect to the head piece and turning with the head piece in its various positions with respect thereto; a rotatable sleeve in threaded engagement with the rod; and a spring for maintaining the sleeve in engagement with the head piece and for maintaining the head piece in engagement with the casing through the intermediation of the sleeve whereby the sleeve and head piece are prevented from moving back and forth.

4. In a reflecting electric lamp, the combination with a reflector carrying casing; of an electric lamp bulb; a shell carrying the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one upon the plug; a motion-transmitting rod extending from the plug and operable from the exterior of the casing to turn said plug; a head piece for the rod and engaged with the casing to confine it to a single plane of rotation, said rod being movable longitudinally and with respect to the head piece and turning with the head piece in its various positions with respect thereto; a rotatable sleeve in threaded engagement with the rod; and a spring for maintaining the sleeve in

engagement with the head piece and for maintaining the head piece in engagement with the casing through the intermediation of the sleeve whereby the sleeve and head piece are prevented from moving back and forth.

5. In a reflecting lamp, the combination with a reflector carrying casing; of an electric lamp bulb; a shell carrying the lamp bulb at its front end; eccentrically disposed complementary switching contacts within the casing for cutting the lamp in and out of circuit; a plug mounted to turn in the shell to have alternative positions to cut the lamp in and out of circuit and having bayonet pin and slot engagement with the shell in the alternative positions of the plug; a rod connected with said plug and projecting through the casing; a head piece for said rod upon the exterior of the casing; and a spring interposed between the casing and the plug and engaging these parts to maintain said head piece in engagement with the exterior of the casing.

6. In a reflecting lamp, the combination with a reflector carrying casing; of an electric lamp bulb; a shell carrying the lamp bulb at its front end; eccentrically disposed complementary switching contacts within the casing for cutting the lamp in and out of circuit; a plug mounted to turn in the shell to have alternative positions and in actuating relation to one of said switching contacts; a rod connected with said plug and projecting through the casing; a head piece for said rod upon the exterior of the casing; and a spring interposed between the casing and the plug and engaging these parts to maintain said head piece in engagement with the exterior of the casing.

7. In a reflecting electric lamp, the combination with a reflector carrying casing; of an electric lamp bulb; a shell carrying the lamp bulb at its front end and having bayonet pin and slot connection with the base of the lamp bulb; eccentrically disposed switching contacts within the casing for cutting the lamp in and out of circuit; a plug within the casing and mounted to turn in the shell to have alternative positions to cut the lamp in and out of circuit and having bayonet pin and slot engagement with the shell in the alternative positions of the plug; a rod extending from said plug and operable from the exterior of the casing for turning the plug; spring means for holding said contacts in engagement to establish circuit and operating to hold the plug in circuit opening and circuit closing positions; a head piece for the rod; and a spring for maintaining the head piece in engagement with the casing.

8. In a reflecting electric lamp, the combination with a reflector carrying casing; of an electric lamp bulb; a shell carrying

the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one upon the plug; a motion transmitting rod extending from the plug and 5 operable from the exterior of the casing to turn said plug; a head piece for the rod; and a spring for maintaining the head piece in engagement with the casing.

9. In a reflecting electric lamp, the combination with a reflector carrying casing; of an electric lamp bulb; a shell carrying the lamp bulb at its front end and having bayonet pin and slot connection with the base of the lamp bulb; eccentrically disposed switching contacts within the casing for cutting the lamp in and out of circuit; a plug within the casing and mounted to turn in the shell to have alternative positions to cut the lamp in and out of circuit and having bayonet 15 pin and slot engagement with the shell in the alternative positions of the plug; a rod extending from said plug and operable from the exterior of the casing for turning the plug; spring means for holding said contacts in engagement to establish circuit and operating to hold the plug in circuit opening and circuit closing positions; a head piece for the rod; a spring for maintaining the head piece in engagement with the casing, said rod being movable longitudinally and with respect to the head piece and turning with the head piece in its various positions with respect thereto; and means operable from the exterior of the casing for 20 effecting movement of the shell and the lamp bulb in and out.

10. In a reflecting electric lamp, the combination with a reflector carrying casing; of an electric lamp bulb; a shell carrying the lamp bulb at its front end; a contact carrying plug within the casing and coupled with the shell for supplying current to the lamp and mounted to turn with respect to the shell to cut the lamp in and out of circuit, there being engageable eccentrically located switching contacts in the lamp circuit, one upon the plug; a motion transmitting rod extending from the plug and operable from the exterior of the casing to turn said plug; a head piece for the rod; a spring for 25 maintaining the head piece in engagement with the casing, said rod being movable longitudinally and with respect to the head piece and turning with the head piece in its various positions with respect thereto; and means operable from the exterior of the casing for effecting movement of the shell and the lamp bulb in and out.

11. In a reflecting lamp, the combination with a reflector carrying casing; of an electric lamp bulb, a shell carrying the lamp bulb at its front end; eccentrically disposed complementary switching contacts within the casing for cutting the lamp in and out of circuit; a plug mounted to turn in the shell to have alternative positions to cut the lamp in and out of circuit; a rod connected with said plug; a head piece for said rod upon the exterior of the casing; and a spring interposed between the casing and the plug and engaging these parts to maintain said head piece in engagement with the casing.

In witness whereof, I hereunto subscribe my name this 29th day of January A. D., 1917.

HARRY A. DOUGLAS.
